UNITED STATES PATENT OFFICE.

PETER J. FISCHER, OF CINCINNATI, OHIO, ASSIGNOR OF ONE-THIRD TO NICHOLAS FISCHER
AND ONE-THIRD TO EDWARD J. FISCHER, OF CINCINNATI, OHIO.

TILE CONSTRUCTION.

No. 874,909.

Specification of Letters Patent.

Patented Dec. 24, 1907.

Application filed August 6, 1906. Serial No. 329,340.

To all whom it may concern:

Be it known that I, PETER J. FISCHER, a citizen of the United States of America, and resident of Cincinnati, county of Hamilton, 5 State of Ohio, have invented certain new and useful Improvements in Tile Construction, of which the following is a specification.

The object of my invention is a tile construction, especially for use as a covering for 10 buildings, in which the tile are of a shape such as lends itself readily to manufacture, in which they may be coupled readily to the supporting means and which is strong and durable.

15 I will first describe the invention in connection with the accompanying drawings, in which like parts are indicated by similar reference letters, and will then specifically set it forth in the claims.

20 Referring to the drawings: Figure 1 is a perspective view of a part of a building in the course of construction, the walls of which are supplied with a tile construction embodying my invention. Fig. 2 is a vertical sectional view upon an enlarged scale through line $x-x$ of Fig. 1. Fig. 3 is a perspective view upon a still more enlarged scale of one of the tile inverted.

25 Referring to the parts: the tile embodying my invention are formed with flat external and internal faces, a , and a' . The upper and lower faces are made at an acute angle to the front face, a , and with the rear part of the face, a^2 , in a higher plane than the forward part of the face, a^3 , leaving a step, a^4 , between them. In the face, a' , a longitudinal groove, a^5 , is cut which in the vertical position of the tile inclines from the face, a' , upward at an angle to the horizontal. The 30 ends of the tile have notches cut into them extending at one end from the front face half way in and at the other end from the rear face half way into the tile. Or, in other words, each tile might be considered to be 35 made up of two equal parallelepipeds in which the upper and lower faces meet the front and rear faces at an acute angle respectively, the said parallelepipeds being placed together, so that the inner one stands

slightly above the outer one and with the 50 ends out of register with each other.

The tiles are secured to the wall of a building by means of metallic lugs which project outward from the wall at an angle thereto, similar to the angle of the groove, a^5 , to the 55 face, a' , the said lugs being made of a width such as to fit the groove, a^5 , snugly.

In Fig. 1 the supporting lugs, b , are struck outward from a piece of sheet metal, B, the lugs, b , being arranged in a series of horizontal lines, the successive lines being at a distance apart equal to the height of the tile, the lugs in one row being preferably staggered with the lugs in the adjacent row. Sheet, B, may be secured to the sheathing, c, 60 of the building, or may be secured to the uprights, C, thereof. After the sheet, B, has been thus secured, the tiles are put upon the supporting lugs, b , starting with the lower row first, the operation being simply to push 65 the tile so that the lugs, b , project into the groove, a^5 , the tiles in one row being arranged so that the ends of one project over the ends of the adjacent tile. When the 70 tiles are secured in place, it is seen that the upper and lower faces fit into the corresponding faces of the adjacent rows, so that the 75 angularity of the face, together with the steps, a^4 , prevent the entrance of moisture to the internal faces of the tile. 80

The method of securing the tile upon the lugs is the same as that aforescribed.

What I claim is:

The combination of a vertical sheet metal wall with metal lugs struck upward at an 85 angle therefrom and arranged in a series of horizontal lines, tiles with flat faces to fit against the metal wall with upwardly inclined slots extending inward from said faces and with their edges inclined from the 90 said faces downward, the lower edges of each row of tiles fitting over the upper edges of the next lower row of tiles.

PETER J. FISCHER.

Witnesses:
